UNITED STATES PATENT OFFICE.

RICHARD AMBERTON, OF LONDON, ENGLAND.

ELECTRIC CONTROLLER

1,391,522.

Specification of Letters Patent. Patented Sept. 20, 1921.

Application filed March 3, 1920. Serial No. 362,947.

To all whom it may concern:

Be it known that I, RICHARD AMBERTON, a subject of the King of Great Britain, and residing at Vauxhall Works, South Lambeth Road, London, S. W. 8, England, have invented certain new and useful Improvements in Electric Controllers, of which the following is a specification.

This invention relates to controllers such as are used for varying the connections or for cutting in or out resistances in electric circuits. It is the object of the invention to reduce or eliminate sparking at the controller contacts by the use of a single contactor arranged in such a manner that it operates repeatedly and substantially performs each successive operation of cutting resistance in or out, or of varying the electrical connections, as the case may be.

20 In the accompanying drawing are shown diagrammatically two forms of electric controllers according to the present invention.

Referring first to Figure 1, the main contact arm or brush *a*, which works over a contact plate *d*, carries an auxiliary contact arm *b* mounted thereon by insulated supports *c*; this auxiliary contact arm *b* works over a contact plate *e* which is adapted to be connected to the plate *d* of the main contact arm *a* and the load circuit *f* through a contactor switch *g*. The coil *o* of the contactor switch *g* is in a circuit *h* which forms a shunt with the load circuit *f*, one end of the circuit *h* being connected to the plate *d*, while the other end is connected to contact studs *j* which are adapted to be brought into electrical connection with controller studs *k'*, *k²*, *k³* by means of the auxiliary contact arm *b*. Between the controller studs *k*, *k'*, *k²*, *k³* are connected the usual resistances *l*, *l'*, *l²*, which are adapted to be cut in or out of the load circuit *f* by the operation of the controller. The studs *j* are so arranged that on the movement of the contact arms *a*, *b*, the gap between the contact studs *j* and the controller studs *k'*, *k²*, *k³*, is only bridged by the contact arm *b* when the latter is fully in contact with the controller stud *k'* and the forward end of the arm *a* is just 45 on the point of leaving the controller stud *k* with which it is in contact, and so that the gap is only broken when the contact arm *a* is fully in contact with the next controller stud *k'* and the forward end of the arm *b* is just beginning to leave the controller stud *k'*.

over which it has been moved. The arm *a* is provided with suitable insulator plates *m*, *n* so as to prevent any electrical connection between the arm *a* and the plate *e* or the studs *j*. The apparatus is shown as controlling an electric motor, whose armature is marked 1 and whose field is marked 2.

60 The operation of the electric controller shown in Fig. 1 is as follows:—

Assuming the main brush *a* to be on one contact *k* and that a step of resistance is to be cut out of circuit, the controller handle is moved forward in the direction of the arrow. The auxiliary contact arm *b* first reaches the next main controller stud *k'*, but 65 as the contactor switch *g* which is normally open, is interposed between it and the load circuit *f*, no current flows.

70 A further forward movement will cause the arm *b* to bridge the gap between the first stud *j* and the second controller stud *k'*, thus closing the circuit *h* and energizing the operating coil *o* of the contactor switch *g*.

75 The contactor switch *g* is thus closed and a step of resistance *l* is cut out of the load circuit *f*, the current now flowing through the plate *d*, contactor switch *g*, plate *e*, contact arm *b*, controller stud *k'* and resistances *l'*, *l²*. The arm *a*, however, still makes connection between the plate *d* and the stud *k*, 80 but with the resistance *l* in circuit.

85 As the forward movement is continued the main brush *a* leaves stud *k* and reaches the stud *k'* but the resistance *l* having been cut out as previously described and the contact 90 arm *b* being still fully in contact with the stud *k'* no deleterious sparking occurs. A slightly further forward movement disestablishes the contact between the arm *b* and the intermediate stud *j* and the contactor switch circuit *h* is opened, leaving the circuit closed through arm *a* and stud *k'*. The controller is now ready to be moved forward to cut out the next step of resistance, when the cycle of operations will be the same as 95 previously described. On moving backward to cut in resistance, these operations are reversed, as it will be seen that on cutting in a step of resistance, the circuit through the auxiliary arm *b* will be broken at the contactor *g* when the arm *b* leaves a stud *j*, but the arm *a* will then be fully in contact with the stud of the controller which connects the further step of resistance in 100 circuit.

105

In addition to the studs *j*, other studs may be provided which are adapted to be connected to operating coils of other contactor switches, their circuits being opened 5 or closed by the passage either of the main contact arm *a* or of the auxiliary contact arm *b* over these studs.

An example of such an arrangement is shown in Fig. 2, wherein a second contactor 10 *p* is controlled by the main contact arm *a* passing over studs *q* so as to prevent risk of 15 sparking on the main contact arm if the first contactor fails to operate correctly.

The general arrangement according to 15 Fig. 2, corresponds to that described in connection with Fig. 1. According to Fig. 2 a contactor *p* is provided, the operating coil of which is adapted to be energized for closing the contactor *p* when the arm *a* is in 20 the starting position and by means of a projection *s* thereon which closes a switch *t* of a circuit *u*, *u'* connected to the main load circuit *f*. In the circuit *u* is also arranged a switch *v* which is normally closed but is 25 adapted to be opened by an arm *p'* bearing on the tail piece of switch *v*, when the contactor *p* is closed. The coil *r* is connected to the studs *q* through a resistance *w* and a conductor *x* and to the contactor *g* by the 30 resistance *w*, conductor *y* and contacts *z*.

The studs *q* are so arranged that contact between them and the arm *a* is not broken as the controller arms are moved forward, until the arm *b* makes contact with the next 35 stud *j* and vice versa. The gap between the studs *k*, *k'*, *k²* and *k³* and between the studs *j* and *q* is of course always such that it is impossible for either the arm *a* or the arm *b* to bridge the gap between the respective 40 studs.

The operation of the controller shown in Fig. 2 is as follows:—

Assuming that the controller is in the starting position and the main switch has 45 been closed, the arm *a*, by means of the projection *s*, will close the switch *t*, and as the switch *v* is normally closed, a current will flow from one terminal of the load circuit *f*, through circuit *u*, switches *t* and *v*, coil *r* and conductor *u'*, to the other terminal of the load circuit *f*. The contactor *p* is thus 50 closed and the switch *v* is opened by means of the arm *p'*. As the main arm *a* is also on the first stud *q* a current will flow from the load circuit *f*, conductor *f'*, contactor *p*, plate *d*, arm *a*, stud *q*, conductor *x*, resistance *w*, coil *r*, conductor *u'* to the other end of the load circuit *f* and thus keep the contactor *p* closed. The main current will now 55 also flow from the arm *a*, through stud *k* and the resistances *l*, *l'*, *l²*, to the motor. 60

In order to cut out a step of resistance *l* 65 from the load circuit *f*, the controller will be moved in the direction of the arrow and the arm *b*, when it comes into contact with

the first stud *j*, will close the circuit *h* of the contactor *g* as in Fig. 1. In addition to this operation, however, the circuit of the contactor *p* must be kept closed and for this purpose the contactor *g* when operated, must 70 also close contacts *z* so as to form a shunt circuit which passes from the contactor *g*, contacts *z*, conductor *y*, resistance *w*, coil *r* and conductor *u'* to the other terminal of the load circuit *f*. The contactor *p* is thus 75 kept closed during the operation of the controller. If, however, the contactor *g* fails to act, then the circuit of the operating coil *r* of the contactor *p* would be deenergized and the main circuit broken at *p* without 80 any deleterious sparking occurring when the arm *a* leaves the stud *q*. This occurs before the arm *a* leaves the stud *k* so that any deleterious sparking is avoided. The controller is now ready to be moved forward to cut 85 out the next step of resistance, when the cycle of operations will be the same as previously described.

For the purpose of cutting in resistance, the operations are reversed, as it will be 90 seen that on cutting in a step of resistance, the circuit through the auxiliary arm *b* will be broken at *g* when the arm *b* leaves a stud *j*, but the arm *a* will then be fully in contact with the stud of the controller which cuts 95 in a further step of resistance in the load circuit, and this arm *a* will also be in contact with a stud *q* so that the coil *r* remains energized and consequently holds the contactor *p* in the closed position.

Having thus described my invention what I claim as new and desire to secure by Letters Patent is:—

1. An electric controller comprising a plurality of contact plates, a plurality of contact studs, a plurality of resistance studs, resistances connected to said studs, a main contact arm, said contact arm being adapted to form electrical connection between one contact plate and the resistance studs, an auxiliary contact arm, said auxiliary contact arm forming electrical connection between a second contact plate, the resistance studs and the contact studs, a contactor adapted when operated to form electrical 105 connection between the contact plates, and electrical means for operating said contactor, said electrical means being controlled by the auxiliary contact arm in such a manner that the contactor operates repeatedly 110 and substantially performs each successive operation of cutting resistance in and out, and of varying the electrical connections.

2. In an electric controller comprising a plurality of contact studs, a plurality of resistance studs and resistances connected to the resistance studs, the combination with the main contact and auxiliary contact making members operatively connected therewith of a contactor, electrical means for 125 130

operating the contactor and controlled by the main contact, said electrical means being so arranged that the contactor operates repeatedly and substantially performs each successive operation of cutting resistance in and out, and of varying the electrical connections.

3. In an electric controller the combination comprising a main contact arm, an auxiliary contact arm, a contactor, and electrical means for operating said contactor, electric circuits, said electric circuits being adapted to be controlled by said contactor, said electrical means being controlled in such a manner by the auxiliary contact arm that the contactor makes and breaks successive circuits in advance and separately from the main contact arm.

4. In an electric controller the combination comprising a main contact arm, an auxiliary contact arm, a contactor, a plurality of resistances, electrical means for operating the contactor, said electrical means being controlled by the auxiliary contact arm in such a manner that when resistances are cut in and out the make and break in the circuit is effected by the contactor.

5. In an electric controller the combination comprising a plurality of contact plates, a main contact arm and an auxiliary contact arm, the main contact arm being adapted to contact with one of the contact plates and the auxiliary contact arm with a second contact plate, a contactor adapted when operated to connect the two contact plates, and an electric operating circuit for said contactor, said operating circuit being controlled by the auxiliary contact arm.

6. In an electric controller the combination comprising a plurality of contact plates, a main contact arm and an auxiliary contact arm, the main contact arm being adapted to contact with one of the contact plates and the auxiliary contact arm with a second contact plate, a contactor adapted when operated to connect the two contact plates, an electric circuit including an operating coil for the contactor and contact studs, said contact studs being so arranged in the path of the auxiliary contact arm that the said contact arm does not make contact with one of the contact studs until it is fully in contact with a resistance stud and while the main contact arm is still in contact with the preceding resistance stud, and that contact between the contact stud and the auxiliary contact plate is only broken when the main contact arm is fully in contact with the next resistance stud and before the auxiliary contact arm commences to leave said contact stud.

7. In an electric controller the combination comprising a main contact arm, an auxiliary contact arm, a contactor, an electric operating circuit for said contactor, said cir-

cuit being controlled by the auxiliary contact arm, a circuit breaker, and electrical operating means for said circuit breaker, said electrical means being controlled by the contactor.

70

8. An electric controller comprising in combination two contact plates, a main contact arm, as auxiliary contact arm, the main contact arm being adapted to contact with one of the contact plates while the auxiliary contact arm contacts with the second contact plate, a contactor between the two plates, an electric circuit including an operating coil for said contactor and contact studs arranged in the path of the auxiliary contact arm, resistances with studs in the path of the main contact arm and of the auxiliary contact arm, a circuit breaker, and an electric circuit including an operating coil for the circuit breaker, said circuit being controlled by the contactor.

75

9. An electric controller comprising in combination two contact plates, a main contact arm, an auxiliary contact arm, the main contact arm being adapted to contact with one of the contact plates while the auxiliary contact arm contacts with the second contact plate, a contactor between the two plates, an electric circuit including an operating coil for said contactor and contact studs arranged in the path of the auxiliary contact arm, resistances with studs in the path of the main contact arm and of the auxiliary contact arm, a second series of studs arranged in the path of the main contact arm, a circuit breaker, an operating coil for said contact breaker, electrical means connecting the operating coil to the second series of studs, and electrical means for controlling the circuit breaker by means of the contactor.

80

85

90

95

100

105

10. An electric controller comprising in combination two contact plates, a main contact arm, an auxiliary contact arm, the main contact arm being adapted to contact with one of the contact plates while the auxiliary contact arm contacts with the second contact plate, a contactor between the two plates, an electric circuit including an operating coil for said contactor and contact studs arranged in the path of the auxiliary contact arm, resistances with studs in the path of the main contact arm and of the auxiliary contact arm, a second series of studs arranged in the path of the main contact arm, said second series of studs being so arranged that the main contact arm does not leave any one of the second series of studs until the auxiliary contact arm is in contact with its corresponding stud of the first series of studs and so that the auxiliary contact arm does not leave its stud of the first series of studs until the main contact arm is in contact with the next stud of the second series of studs in its path, a circuit breaker, an operating coil for said contact breaker, elec-

trical means connecting the operating coil to the second series of studs, and electrical means for controlling the circuit breaker by means of the contactor.

- 5 11. In an electric controller the combination comprising two contact plates, resistance studs and resistances connected thereto, a main contact arm, an auxiliary contact arm, the main contact arm being adapted to contact with one contact plate and the auxiliary contact arm with the second contact plate, while both the main contact arm and the auxiliary contact arm are adapted to contact with the resistance studs, a contactor be-
10 tween the contact plates, an operating coil for the contactor, contact studs in the path of the auxiliary contact arm and connected to the operating coil, a circuit breaker, an operating coil for said circuit breaker, means
15 for controlling the operating coil of the circuit breaker by the contactor, contact studs in the path of the main contact arm and con-
20

nected to the operating coil of the circuit breaker by electrical connections including a resistance, an electric circuit for the operating coil of the circuit breaker, said circuit including switches one of which is held closed when the main contact arm is in the starting position but is opened as soon as the controller handle is moved from this position 25 when the operating coil is energized by the main contact arm being in contact with one of its studs, while a second switch in said circuit is opened by the circuit breaker when the operating coil thereof is energized, and 30 electrical connection between the contactor and the operating coil of the circuit breaker, the arrangement being such that the circuit breaker remains closed during the operation of the main contact arm unless the contactor 35 fails to act when the circuit breaker is opened.

RICHARD AMBERTON.
